UNITED STATES PATENT OFFICE

2,583,974

FUEL PUMP CYLINDER AND PISTON

Caleb E. Summers, Orchard Lake, Mich.

Original application August 14, 1943, Serial No. 498,699, now Patent No. 2,414,617, dated January 21, 1947. Divided and this application January 9, 1947, Serial No. 720,993

1 Claim. (Cl. 309—3)

1

The present invention relates to cylinders and pistons specifically for gasoline or similar light low viscosity fluids.

In impulse pumps for gasoline and the like, particularly when a high or moderately high pressure delivery is required, it is necessary that there be a very close and accurate fit of the piston in the cylinder, and in ordinary methods it is difficult, expensive, and sometimes impossible to obtain such fits.

Among the objects of the present invention is a method of obtaining the necessary close fitting of the piston in its cylinder that will be inexpensive both in time and equipment.

Another object is a cylinder and piston produced by such method.

Further, even with the close fit obtainable by the present method, if very high delivery pressures are to be had, additional means for preventing leakage of the light liquid past the piston are desirable.

It is, therefore, also among the objects of the invention to provide such additional means.

Still other objects and advantages will be apparent to those skilled in the art upon reference to the following description and the accompanying drawings in which

Figure 1 is a central longitudinal sectional view of a cylinder and piston embodying the present invention.

Figure 2 is a section on line 2—2 of Figure 1.

The present application is a division of my copending application Serial No. 498,699, filed August 14, 1943, now Patent No. 2,414,617, on Fuel Metering, and Injection Pumps, and Figure 1 of the present drawing is a part of Figure 1 of that application.

In the drawing, the cylinder 11 of suitable material is shown as provided with a liner 16 of steel or other suitable material, which liner is provided outside and in with circumferential grooves 17 and 18. These grooves are of considerable width as shown and arranged so that there is a small overlapping. The inside of liner 16 is provided with a substantial coating 16A of silver, cadmium or tin, preferably the latter.

Fitted within the cylinder liner 16 is a piston 30, shown in the form of a rod, having at its rearward end a roller cam follower 32 adapted to coact with a cam 33. This cam 33 provides for the delivery or forward stroke of the piston 30 while the return or suction movement is through the action of a suitable spring 31.

At the forward end of the cylinder 11 is fixed a member 20 having a pump chamber 21, an out-

2

let 25 controlled by a valve 26, and a valve 23 controlling an inlet 22.

As stated above, in pumps adapted to deliver light liquids, such as gasoline, it is necessary that the piston have as little clearance in the cylinder as is possible. So, in producing the present structure, the liner 16 is electroplated on the inside with one of the metals mentioned above, preferably tin, to provide a coating sufficiently thick to reduce its inside diameter to a dimension slightly less than the diameter of the piston 30. The latter, or a special broach, is then forced into the cylinder and liner so that the excess of the soft metal is displaced by consolidation or partial removal or both, and substantially no piston clearance results.

This, in itself, will give good results in the use of the pump, but as a further prevention, of leakage past the piston, an oil inlet 16K leading to the central inside groove 18 is provided and oil under pressure is forced in.

The pressure of such oil should be somewhat higher than the average pressure built up in chamber 21 so that any movement of fluid past the piston is toward chamber 21 rather than away from it.

The grooves 17 and 18 are provided to prevent decrease in the inside diameter of the liner due to any greater contraction of the cylinder 11, if the latter should be made of metal having a much greater coefficient of expansion than that of the liner.

Now having described the invention and the preferred embodiment thereof, it is to be understood that said invention is to be limited, not to the specific details herein set forth, but only by the scope of the claim which follows.

I claim:

40 In a fuel pump of the cylinder and piston type, a body of metal having a relatively high coefficient of expansion, and a piston of relatively low coefficient of expansion, a sleeve lining mounted in said body and in which said piston is reciprocable, said sleeve being also of relatively low coefficient of expansion, means for maintaining piston clearance under varying temperature conditions, said means consisting of annular relieved portions inside and outside of said sleeve, said outer and inner relieved portions alternating longitudinally throughout the length of the sleeve and slightly overlapping.

CALEB E. SUMMERS.
